UNITED STATES PATENT OFFICE.

WILLIAM F. GUERIN, OF BROOKLYN, NEW YORK.

SNOW-REMOVAL AND STEAM-HEATING SYSTEM.

1,350,968.

Specification of Letters Patent. Patented Aug. 24, 1920.

Application filed March 29, 1920. Serial No. 369,583.

To all whom it may concern:

Be it known that I, WILLIAM F. GUERIN, a citizen of the United States, and a resident of the city of New York, borough of Brooklyn, county of Kings, and State of New York, have invented a new and Improved Snow-Removal and Steam-Heating System, of which the following is a full, clear, and exact description.

10 This invention relates to means for the removal of snow, and has reference more particularly to a snow removal and steam heating system which includes a steam pipe located adjacent the points where the snow accumulates, said steam pipes being adapted to melt the snow and cause the resulting water to flow away.

15 An object of this invention is to provide means for quickly and cheaply freeing 20 streets and side walks of heavy snow falls.

Reference is to be had to the accompanying drawing forming a part of this specification, in which it is understood that the drawing illustrates only one form of the invention, and in which—

Figure 1 is a plan view partly in section of a building surrounded by the steam pipes of my improved system.

Fig. 2 is a sectional view showing the arrangement of my system with respect to the street.

Fig. 3 is a perspective view on a large scale showing a workman shoveling snow into the trench which contains the steam pipe.

Fig. 4 is a sectional view through the trench containing the steam pipe.

Fig. 5 is a plan view of one of the trench covers.

40 Fig. 6 is a bottom view of one of the trench covers.

Referring to the accompanying drawing by numerals, 10 indicates the walls of a building which contains steam boilers 11 and is surrounded by a side walk 12 adjacent a paved street 13. The paved street usually slopes down so as to form a gutter adjacent the sidewalk, and a trench 14 is formed in this gutter and is covered by removable covers 15 which are constructed in sections so that the weight of each cover will not be excessive, each cover being reinforced on its under side by ribs 16. One or more steam pipes 17 are provided in the trench 14 supported on brackets 18, and these brackets are secured to the wall of

said trench by bolts 19. The covers 15 may be made substantially water tight by any gasket 20 between said cover and the wall of said trench so that the waste water accumulating in the gutter during rainy summer seasons will run down the gutter over the covers to its usual man-hole. The steam pipe may extend all the way around the building and return again to the building 60 so that the uncondensed steam can be used for heating the building. A water outlet 21 may be provided in the bottom of the trench 14 at suitable intervals, said outlet extending to a man-hole 22 in the center of the 65 street 13, which leads into a sewer 23. Steam traps 24 are placed at suitable intervals along the pipe 17 so that the water formed by the condensation of the steam in the pipes will be discharged into the trench. 70

75 Thus in the winter when a large quantity of snow falls, the covers 15 may be removed and the snow shoveled into the trench 14. Steam can be then forced through the pipe 17 thus melting the snow and causing it to 80 flow away as water through the outlet 21 into the sewer 23. This will provide a very quick, cheap, and efficient means of removing snow in cities.

I would state in conclusion that while the 85 illustrated example constitutes a practical embodiment of my invention, I do not limit myself strictly to the mechanical details herein illustrated, since manifestly the same can be considerably varied without departure from the spirit of the invention as defined in the appended claim. 90

Having thus described my invention, I claim as new and desire to secure by Letters Patent:

95 In a snow removal system, the combination with a street, a sewer and a source of steam, of a trench formed in the gutter of said street, a steam pipe positioned in said trench, a plurality of covers over said trench adapted to be removed so that snow and ice can be thrown into said trench to be melted by the heat from said steam pipe, an oblique outlet pipe connecting the bottom of said trench with said sewer, and a steam 100 trap on said steam pipe adapted to discharge water of condensation into said trench so that said water will mix with the water from the melted snow and run through said outlet pipe into said sewer. 105

WILLIAM F. GUERIN.
